[57] **CLAIM**

The ornamental design for a Makarov handgun loader assist, as shown and described.

DESCRIPTION

FIG. 1 is a perspective view of a Makarov handgun loader assist showing my new design;
FIG. 2 is a right side elevational view with the left side being a mirror image thereof;
FIG. 3 is a bottom view thereof;
FIG. 4 is a front elevational view thereof;
FIG. 5 is a top view thereof; and,
FIG. 6 is an environmental perspective view of a Makarov handgun loader assist with the loader assist in an alternate position, showing the movement of the loader assist.
The broken line showing of a hand and a magazine is for illustrative purposes only and forms no part of the claimed design.
